CONTROL SYSTEM

Vernon R. Kimball, Maywood, and Adam Drenkard, Jr., Teaneck, N. J., assignors to Bendix Aviation Corporation, Teterboro, N. J., a corporation of Delaware

Application September 22, 1949, Serial No. 117,218

10 Claims. (Cl. 343—100)

1

The present invention relates to the remote control of movable members, and particularly to orienting directional antennas used for transmission or reception of electromagnetic waves as in radar, television or microwave relay communication systems.

As is well known, maximum signal intensity is obtained with a directional antenna when the plane of the antenna is normal to a line between the antenna and a distant station. When signals are selectively transmitted to or received from a plurality of distant stations located in different directions from the point of transmission or reception, the antenna must be oriented so that signal intensity is a maximum with respect to the selected station.

With equipment used heretofore to microwave television programs from the point of origin to the central station for general telecast distribution, the antenna is "aimed" by locally manually moving the antenna each time the location of a remote program is changed. The antenna is at a considerable distance from the control room where the accuracy of its position is measured by the resultant signal strength, and instructions to personnel "aiming" the antenna must be relayed between the two points. Often the antenna is so inaccessible that repositioning it frequently requires the services of a special rigging crew. As a result, the expense, time and other difficulties in repositioning the antenna impose limitations on the frequency and speed with which programs can be switched from one remote point to another.

One object of the invention is to automatically position an antenna from a remote point for maximum signal intensity relative to any one of a number of selected stations.

Another object is to provide manually controlled means remote from the antenna for positioning the antenna.

Another object is to manually or automatically position, in azimuth and elevation and from a remote point, an element rotatable about horizontal and vertical axes.

The invention contemplates a control system including means, such as a plurality of transmitting inductive devices, providing predetermined phase-voltage signals corresponding to predetermined positions of a movable element, such as an antenna to be positioned for maximum signal intensity with respect to distant stations. Signal responsive means, such as a servo, may be connected by circuit closing means to a selected one of the transmitting inductive devices

5 to drive the antenna to the desired position. A transmitter inductive device, in which the signal may be varied manually or otherwise, also may be provided to position the antenna. A separate control system preferably is used for accurately positioning the antenna about its horizontal and vertical axes.

10 The foregoing and other objects and advantages of the invention will appear more fully hereinafter from a consideration of the detailed description which follows, taken together with the accompanying drawing wherein one embodiment of the invention is illustrated. It is to be expressly understood, however, that the drawing is for illustration and description only, and is not to be construed as defining the limits of the invention.

In the drawing,

15 Figure 1 is a side view, partly in section, of an antenna assembly constructed according to the invention; and

20 Figure 2 is a wiring diagram showing the circuit arrangement in the antenna system.

25 In Figure 1, an antenna base 1 is mounted in bearings 3 on a support 4 for azimuth rotation about a vertical axis. A servo 5 drives base 1 in azimuth through gears 7, 9.

30 An antenna 11 of any suitable kind is supported by a member 12 pivoted for limited elevation rotation about a horizontal axis 13 to an upright 15 rigid with base 1. A servo 17 drives the antenna and supporting member in elevation through an arm 19 and link 21.

35 In Figure 2, an azimuth antenna control circuit 23 is shown at the left-hand side of the drawing, and an elevation antenna control circuit 25 is shown at the right hand side of the drawing. The electrical components of the azimuth and elevation controls are substantially identical.

40 The azimuth control includes a plurality of transmitting inductive devices 27, the number corresponding to the number of stations to which the antenna is to be directed automatically, and each device includes a rotor 29 and a stator 31. Each rotor 29 is energized by an alternating power source 48 and preferably is pre-set relative to the associated stator 31 to provide a predetermined phase-voltage signal corresponding to the station to which the antenna is to be directed.

45 Azimuth servo 5 includes a receiver inductive device 33 having a rotor 35 and a stator 37 which 50 may be connected selectively by switches or other

circuit connecting devices 39 to stators 31 of transmitter inductive devices 21.

Servo 5 also includes an amplifier 41 and a two-phase motor 43 having one of its fields 45 excited by the amplifier output and having its other field 47 separately excited from a source 48 of the same frequency as the signal frequency. Motor 43 drives antenna base 1 through gears 7, 9, and is connected mechanically to rotor 35 of receiver inductive device 33.

The signal from a preselected transmitter inductive device 27 connected to the servo by its associated switch 39 is fed to receiver inductive device 33 and the error signal is amplified and impressed on field 45 of motor 43. The motor operates until the receiver inductive device is driven to null position and orients the antenna in azimuth to a position at right angles to the line between the antenna and the selected station.

Likewise, a plurality of transmitter inductive devices 49, set for predetermined signals corresponding to elevation positions of the antenna, may be connected selectively by their associated switches 51 to elevation servo 17, which includes a receiver inductive device 53, an amplifier 55 and a motor 57. Motor 57 pivots antenna member 12 through arm 19 and link 21, and drives receiver inductive device 53 to null position.

If the distant stations are located to the north, south and east, respectively, of the antenna, then the antenna may be directed to the station to the north by closing uppermost switches 39, 51, for the station to the south by closing the lowermost switches 39, 51, and for the station to the east by closing the intermediate switches 39, 51.

In the drawing, only three of each of the pre-set inductive devices 27, 49 are shown, but it should be understood that any number of such devices may be provided corresponding to the number of stations to which the antenna is to be directed automatically.

Adjustable transmitter inductive devices 59, 61, may be provided for manually positioning the antenna in azimuth and elevation, respectively, such as in picking up mobile units. Transmitter inductive devices 59, 61 may have control knobs 63, 65, and may be connected by switches 67, 69 to azimuth and elevation servos 5 and 17, respectively. The signals from inductive devices 59, 61, are impressed on receiver inductive devices 33, 53, and motors 43, 57, in response to the error signal, drive the antenna to desired position. Dials 71, 73, may be provided to indicate the azimuth and elevation positions of the antenna.

The antenna may be continuously rotatable in azimuth, or may be provided with suitable means, such as disclosed and claimed in co-pending application Serial No. 147,342, filed March 3, 1950, by Irving B. Cooper, Jr., for limiting rotation in azimuth to approximately one revolution in either direction.

The antenna may be automatically positioned for maximum signal intensity with respect to any selected station by closing azimuth and elevation switches 39, 51, corresponding to the selected station, or the antenna may be directed to a mobile or other station by closing switches 59, 61 and manually manipulating knobs 63, 65.

Although the control system has been illustrated and described in detail only in connection with positioning an antenna, it should be understood that the invention is not limited thereto and that the control system may be used for

orienting an element of any kind to a desired position. For example, the antenna may be replaced by a television camera and a number of such cameras may be located at various vantage points in an assembly hall or stadium, and be individually controlled manually or automatically from a central control booth. This arrangement will offer a broad scope of coverage and a great variety of camera angles with but a single operator. Various changes can be made in the design and arrangement of the parts without departing from the spirit and scope of the invention as the same will now be understood by those skilled in the art.

What is claimed is:

1. In an antenna system, an antenna to be positioned, inductive means for generating a plurality of predetermined signals corresponding to predetermined positions of said antenna, means responsive to said signals for driving said antenna to said positions, and means for selectively impressing one of the signals of said signal generator means on said signal responsive means.
2. In an antenna system, an antenna to be positioned, pre-set inductive means for effecting a plurality of predetermined signals corresponding to predetermined positions of said antenna, means responsive to said signals and drivingly connected to said antenna, and circuit closing means for selectively connecting said signal responsive means to said inductive means for impressing one of the signals of said inductive means on said signal responsive means and actuating said responsive means to drive said antenna to one of said predetermined positions.
3. In a control system, an element to be positioned, a plurality of transmitter inductive devices providing predetermined signals corresponding to predetermined positions of said element, a servo including a receiver inductive device and a motor drivingly connected thereto and to said element, and circuit closing means for selectively connecting one of said transmitter inductive devices to said receiver inductive device, said motor being responsive to the error signal of said transmitter and receiver inductive devices and driving said receiver inductive device to null position and driving said element to a corresponding predetermined position.
4. In an antenna system, an antenna rotatable about horizontal and vertical axes, a control for positioning said antenna about each of said axes, said control including a plurality of pre-set inductive means for effecting a plurality of predetermined signals corresponding to predetermined positions of said antenna about one of said axes, means responsive to said signals for driving said antenna about one of said axes to said positions, and means for selectively impressing one of the signals of said pre-set means on said signal responsive means.
5. In an antenna system, an antenna rotatable about mutually perpendicular axes, a control for positioning said antenna about each of said axes, said control including a plurality of transmitter inductive devices providing predetermined signals corresponding to predetermined positions of said antenna about one of said axes, a servo including a receiver inductive device and a motor mechanically and electrically connected thereto and operatively connected to said antenna for rotating said antenna about one of said axes, and circuit closing means for selectively connecting one of said transmitter inductive devices to said receiver inductive device to operate said

motor in response to the associated signal and to drive said receiver inductive device to null position and drive said antenna about one of said axes to one of said predetermined positions.

6. In an antenna system, an antenna to be positioned, manually operated inductive means for generating a series of electrical signals corresponding to different positions of said antenna, and means responsive to said signals and connected to said signal generating means and driving said antenna to said positions.

7. In an antenna system, an antenna to be positioned, a transmitter inductive device, means for changing the output signal of said transmitter inductive device, a receiver inductive device connected electrically to said transmitter inductive device, and a motor drivingly connected to said receiver inductive device and to said antenna, said motor being responsive to the error signal of said transmitter and receiver inductive devices and driving said receiver inductive device to null position and driving said antenna to a corresponding position.

8. In a control system, an element to be positioned, a plurality of pre-set transmitter inductive devices each providing a predetermined signal corresponding to a predetermined position of said element, an adjustable transmitter inductive device having means for changing its output signal, a servo including a receiver inductive device and a motor drivingly connected thereto and to said element, and circuit closing means for selectively connecting one of said transmitter inductive devices to said receiver inductive device, said motor being responsive to the error signal of said connected transmitter and receiver inductive devices and driving said receiver inductive device to null position and driving said element to a corresponding position.

9. In combination with a positionable element adapted for movement to a plurality of preselected positions, a motor drivably connected to said element, a signal responsive device for operating said motor, a plurality of inductive signal generators for generating signals representing the preselected positions of said element, and means for selectively connecting said signal generators to said signal responsive device.

10. In combination with a positionable element adapted for movement to a plurality of preselected positions, a motor drivably connected to position said element, a two-part inductive signal responsive device having one part thereof operating said motor, a plurality of two-part inductive signal generating devices for generating signals representing the preselected positions of said element, one part of each of said last-named signal generating devices being connected to a common source of supply and the other part of each of said signal generating devices being adapted for connection to the other part of said signal responsive device, and means for selectively connecting said signal generators to said signal responsive device.
